United States Patent Office

Des. 198,455
Patented June 16, 1964

198,455

BLOCK WALL

Raymond W. Clanton, 9735 Orcas Ave., Sunland, Calif.

Filed Dec. 30, 1963, Ser. No. 77,972

Term of patent 14 years

(Cl. D18—2)

FIG. 1 is an elevational view of one side of a portion of a block wall showing my new design;

FIG. 2 is a plan view; and

FIG. 3 is a sectional view on line 3—3 of FIG. 1.
The two sides of the wall are the same in appearance.
I claim:

The ornamental design for a block wall, substantially as shown and described.

References Cited in the file of this patent

UNITED STATES PATENTS

1,858,091 Humphris ----- May 10, 1932

OTHER REFERENCES

Architectural Record, May 1957, page 173, grille at top left of page.